UNITED STATES PATENT OFFICE.

CHARLES COX JAMES AND CHARLES WILLIAM JAMES, OF DAYTON, OHIO;
EDWIN C. JAMES ADMINISTRATOR OF SAID CHARLES C. JAMES, DE-
CEASED.

STOCK-CAR.

SPECIFICATION forming part of Letters Patent No. 327,880, dated October 6, 1885.

Application filed July 9, 1885. Serial No. 171,100. (No model.)

To all whom it may concern:

Be it known that we, CHARLES COX JAMES and CHARLES WILLIAM JAMES, of Dayton, in the county of Montgomery and State of 5 Ohio, have invented certain new and useful Improvements in Stock-Cars; and we do hereby declare that the following is a full, clear, and exact description, of the invention which will enable others skilled in the art to which it applies to make and use the same, reference being had to the accompanying drawings, and to the letters of reference marked thereon, which form part of this specification.

Our invention consists in the combination 15 and arrangement of certain mechanical devices to be utilized in the construction of a combined stock and coal car.

In explanation of the title of the invention the car is so constructed as to permit its conversion into either an open or closed car.

Referring to the drawings, Figure 1 is a side elevation showing the car as open and adapted to haul coal; Fig. 2, a side elevation showing the car as closed and ready for use as 25 a stock-conveyer.

Like letters of reference indicate corresponding parts in all the figures.

A is the car, having ordinary stringers, draw-bars, and truss-rods, and suitably 30 mounted on trucks, but which are not shown, as they form no part of our invention.

B is the outside door, adapted to slide along on track or rod *a* back to open position, as shown in Fig. 1.

35 C C are sliding doors or sections, which run along rods on the top and inside of the car, and slide behind door B when the car is open.

The outside door, B, is provided with an angle-iron, *e*, which is bent at its end to engage the recess between the track (upon 40 which it slides) and the car, said track being secured to the top of the car by bolts or rivets.

This door, as well as the others, is constructed of slats or beams with apertures 45 between for the admission of the air, and is suitably braced by cross-beams, &c., as is common in the construction of the doors and sides of transporting-cars. The doors or sections C C are also provided with a pro-

jecting iron or catch at their upper sides to

engage the recess between the inside track upon which they slide.

The door B is made the whole height of the car, and the doors or sections C may also be made of the same height when desirable; but 55 in this instance we have shown them only occupying half the height of the car-side, the other half being protected by the stationary sections E E.

The manner of fastening the doors C D 60 may be accomplished with any suitable fastener, and hence it is thought unnecessary to show them.

The beams or posts G, which hold and brace the sides of the car, are rigidly secured to the 65 bottom thereof by bolts and a mortise, and at the top by metallic braces, which are secured both to the beams and to the top of the car.

The top of the car is furnished with apertures of a suitable shape for the insertion of 70 chutes of the desired pattern, when it is desired to load from the top of the car. When these chutes are removed, hatchways can be inserted in their stead to cover the apertures.

When it is desired to use our invention for 75 transporting stock, the sides of the car are in the position shown in Fig. 2, with the movable sectional sides in their proper places beside the outside door, and said door is drawn over the supplementary half-door, which is, 80 as before mentioned, used for hauling coal, &c., and may be raised on the stop or catch arranged on the beam above during heated periods, and can be lowered and fastened in cold weather, as the outside door prevents 85 the egress of the stock, and after the removal of the stock, should it be desired to convert the car so that it will be adapted to convey coal or other like materials, the sectional sides are run along on the inside rod back to the 90 position shown in Fig. 1, and the outside door is also run on the outside rod *a* back into a corresponding but opposite position to the said sectional sides. The coal can then be introduced either by the old method or by the 95 chutes herein mentioned.

Having thus described our invention, what we claim as new, and desire to secure by Letters Patent, is—

1. The combination of the movable sec- 100

tional doors of the car and the central outside sliding door with the inside and outside tracks or rods, substantially as set forth.

2. The sides of a combined coal and stock car having the sectional doors sliding on rods inside of car, and the central outside door sliding on rods outside of said car, substantially as described.

In testimony that we claim the foregoing as our own we hereunto affix our signatures to in presence of two witnesses.

CHARLES COX JAMES.

CHARLES WILLIAM JAMES.
